UNITED STATES PATENT OFFICE.

DANIEL MILTON HEALD, OF MILFORD, NEW HAMPSHIRE.

ROUTING-TABLE.

SPECIFICATION forming part of Letters Patent No. 721,950, dated March 3, 1903.

Application filed October 1, 1902, Serial No. 125,564. (No model.)

To all whom it may concern:

Be it known that I, DANIEL MILTON HEALD, a citizen of the United States, residing at Milford, in the county of Hillsboro, State of New Hampshire, have invented certain new and useful Improvements in Routing-Tables; and I do hereby declare the following to be a full, clear, and exact description of the invention, such as will enable others skilled in the art to which it appertains to make and use the same.

This invention relates to routing-tables; and it has for its object to provide a construction including a table proper or base and a rack mounted above the base for rotary movement toward and away from the base to rest thereon or lie in spaced relation thereto, the rotary motion being given to the rack through the medium of spring-actuated mechanism, which serves also to hold the rack yieldably at whatever elevation it may be placed.

A further object of the invention is to provide a construction which will be cheap of manufacture and efficient in operation and which will be light and easy of shipment, other objects and advantages of the invention being understood from the following description.

In the drawings forming a portion of this specification, and in which like numerals of reference indicate similar parts in the several views, Figure 1 is a front elevation of a routing-table embodying the present invention. Fig. 2 is a side elevation of the routing-table with one upright removed and showing the rack in lowered position, the raised position of the rack being shown in dotted lines. Fig. 3 is a perspective view of one of the shelves of the rack, a number of the partition-wires being removed.

Referring now to the drawings, there is shown a routing-table comprising a table proper or base including a top 10, having legs 11, and upon which top, at the ends and rear portion thereof, are the parallel uprights 12, having the connecting back piece 13 at their lower ends and the upper connecting-brace 14. From the uprights to the front edge of the table extend also the side pieces or cheeks 15, which prevent the loose mail-matter from falling off from the table-top. Between the uprights 12 is disposed a rack comprising a casing including end pieces 16 and connecting-shelves 17, the width of the casing being

slightly less than the space between the uprights, as shown, to accommodate the spring-actuated mechanism for lifting the rack and 55 for holding it at different elevations. Each of the shelves of the rack consists of spaced longitudinal slats 18, having transverse connecting end and intermediate pieces 19, the upper faces of said slats and connecting-pieces 60 lying in a common plane. The connecting-pieces extend rearwardly beyond the rear slat 18, and against their rear ends is secured a longitudinal piece 20. In the slats 18, as also in the connecting-pieces 19, are formed perforations 21, and in each transverse pair of perforations are disposed the ends of wire wickets or arches 22, which stand erect and parallel from front to back of the shelf. The wire wickets or arches form partitions, and in 70 the interspaces between them are disposed the letters as they are sorted upon the table-top 10. This construction of shelf is much lighter than the solid board shelf, while possessing all of the required rigidity, the letters 75 being prevented from dropping between the longitudinal slats by means of the longitudinal wires or rods 23, which are disposed between the slats and between the rear slat and the longitudinal piece 20, said wires or rods 80 being parallel with the slats and being set into the faces of the connecting-pieces 19 to lie flush with the upper faces thereof.

During the sorting of first-class mail-matter the rack is adjusted to the desired elevation; but when second-class matter is to be sorted the entire top of the table is required, so that the rack must be raised and held in elevated position free from the table-top.

To raise the rack, levers 25 are pivoted at 90 their rear ends against the inner faces of the uprights 12, while their forward ends are pivoted against the outer faces of the ends of the frame of the rack, said levers when the rack is in lowered position extending from their 95 rear ends downwardly and forwardly.

Projecting from the side faces of the levers are pins 26 in such positions that when the rack is in lowered position said pins will lie vertically below the upper or rear pivots of the levers. Connected to the pins 26 are helical springs 27, which are passed upwardly and are connected at their upper ends to the eyes of eyebolts 28, which are passed upwardly

through the brace 14 and have adjusting thumb-nuts 29 engaged with their upper portions, so that the eyebolts may be drawn upwardly to increase the tensions of the springs 5 or may be released to decrease such tension. With this construction it will be seen that when the rack is in lowered position the axes of the helical springs will lie in the rear of the upper or rear pivots of the lifting-levers. 10 If then the lower end of the rack be drawn forwardly until the axes of the springs pass in front of said rear pivots of the levers, said spring will act to swing the levers on their rear pivots to raise the forward ends of the 15 levers and therewith the rack, movement of the upper end of the rack to correspond to the movement of the lower end thereof being insured by the links 30, which are pivoted to the end pieces 12 and the ends of the rack- 20 frame, said links being at all times parallel with the levers and having the same lengths as the levers between their pivots. When the rack has been moved to the limit of its upward movement, the helical springs 25 hold it against outward swinging movement, the cross-brace 14, which engages in the notches 31 in the ends of the rack-frame, acting as a stop to limit the upward movement of the rack, while the back piece 13 limits 30 the downward movement in connection with the top 10. The friction between the rack and the frame in which it slides is such that the tension of the springs is not sufficient to raise the rack, while the friction and springs 35 together prevent downward movement of the rack. When the rack is to be raised, it is grasped and raised manually and requires no latches to hold it at different elevations.

It will be understood that in practice modifications of the specific construction shown 40 may be made and that any suitable materials and proportions may be used for the various parts without departing from the spirit of the invention.

45 What is claimed is—

1. A routing-table comprising a base, a rack mounted for movement bodily about an axis toward and away from the base, and a spring-actuated mechanism connected with the rack

and disposed to oppose the movement of the 50 rack in the direction of the base.

2. A routing-table comprising a base and a rack mounted for movement bodily about an axis toward and away from the base, means for limiting the movement of the rack and a 55 spring-actuated mechanism connected with the rack for holding it at different points of its movement.

3. A routing-table comprising a base, a rack mounted for movement bodily about an axis 60 toward and away from the base, and a spring-actuated mechanism connected with the rack and disposed to oppose movement of the rack in the direction of the base, and adapted to hold the rack at different points of its move- 65 ment.

4. A routing-table comprising a base having uprights, a rack disposed between the uprights, levers pivoted at opposite ends to the rack and uprights, helical springs connected 70 with the uprights above the pivotal connections of the levers with the uprights and connected to the levers at points between their pivotal connections with the uprights and rack, said levers being movable with the rack 75 to carry the points of connections of the spring below and beyond the points of connections of the levers with the uprights.

5. A routing-table comprising a base having uprights, a rack disposed between the up- 80 rights, levers pivoted at opposite ends to the rack and uprights, helical springs connected with the uprights above the pivotal connections of the levers with the uprights and connected to the levers at points between their 85 pivotal connections with the uprights and rack, said levers being movable with the rack to carry the points of connections of the spring below and beyond the points of connections of the levers with the uprights and means for 90 adjusting the tensions of the springs.

In testimony whereof I affix my signature in presence of two witnesses.

DANIEL MILTON HEALD.
